UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

BODY AND TRUCK BOLSTER.

No. 825,024.

Specification of Letters Patent.

Patented July 3, 1906.

Application filed July 31, 1905. Serial No. 272,046.

To all whom it may concern:

Be it known that I, ETHAN I. DODDS, a citizen of the United States, residing at Pullman, county of Cook, and State of Illinois, have invented certain new and useful Improvements in Body and Truck Bolsters, of which the following is a specification.

In order to make a strong bolster with the lower plate bellied at its central portion, so as 10 to most effectively resist the strains put upon it, I have devised a bolster which includes side plates with integral flanges at their upper and lower edges. The upper flanges are turned outward for substantially the entire 15 length of the plates, while the central lower portion of the plates has outwardly-turned flanges and the intermediate and end portions have inwardly-turned flanges. Coöperating with these lower flanges is a bottom 20 tie-plate which tapers toward its ends, said plate being riveted to the flanges. By using such a tapering tie-plate I not only make the bolster of a shape to effectively withstand its strains, but I also save metal where it is not 25 needed and economize in weight.

The flanges of each bolster-plate may be turned over when the plate is either hot or cold; but I preferably perform the operation when the plate is cold. By this method the 30 metal is not stretched or subjected to attenuation, but remains of a uniform thickness throughout. In addition to these advantages I am enabled to employ a heavy tension-plate at the bottom, and the same can 35 be easily riveted to the flanges of the side plates, because they are readily accessible, being turned outwardly, at least at the central part.

In the accompanying drawings I have 40 illustrated one embodiment of my invention, wherein—

Figure 1 shows a perspective view of my improved truck-bolster. Fig. 2 is a side elevation of the body-bolster. Fig. 3 is a similar view of the truck-bolster. Fig. 4 is a horizontal section of the body-bolster on the line 4 4 of Fig. 2. Fig. 5 is a partial top plan and partial sectional view of the truck-bolster illustrated in Fig. 3. Fig. 6 is a vertical 45 longitudinal section of the body-bolster. Fig. 7 is a vertical longitudinal section of the truck-bolster. Fig. 8 is an end view of both bolsters, and Fig. 9 is a cross-section of both bolsters on the line 9 9 of Fig. 4.

Each bolster comprises two side plates 1 1, 55 each of which has an outwardly-turned flange 2, extending along the greater portion of its upper edge. At the lower edge of each plate is an outwardly-turned flange 3 at the central portion and inwardly-turned flanges 4 at 60 the intermediate inclined and end portions of the sides. A top plate 5 covers the plates 1 1 and is riveted to their upper outwardly-extending flanges 2. A bottom plate 6, which is widest at its central portion 7 and which 65 tapers, as at 8 8, toward its ends, which have parallel edges 9 9, is riveted to the flanges 3 and 4. By means of this tie-plate 6 I securely tie together the lower portions of the plates 1 1 and secure great strength because 70 of the width of the central portion of the tie-plate, which is riveted to the outwardly-turned flanges.

The body-bolster has its side plates 1 1 spaced apart at their ends by means of dish-shaped sheet or cast metal parts 10, which are riveted to the side plates 1 1 and also secured to the flanges 4 and the bottom plate 6. 75

The truck-bolster constructionally follows the body-bolster; but its side plates are 80 spaced apart and strengthened at each end by means of two dish-shaped plates 11 11, these plates being riveted to the side plates 1 1 and also to the lower tie-plate and to the flanges 4 4. This construction is clearly illus- 85 trated in Figs. 1 and 7.

To the lower side of the body-bolster I 90 rivet the center-bearing plate 12, which is provided with an annular rib 13, which acts as a bearing. The plate 12 is secured to the under side of the body-bolster by means of rivets passing through the bottom tie-plate 6 and the central outwardly-turned flanges 3 3.

On the upper side of the truck-bolster I 95 rivet the coöperating center-bearing plate 14, having the annular rim 15, within which fits the rim 13. These two bearing-plates 12 and 14 act together to form a strong and easily-constructed center-bearing. The plate 14 is secured to the top of the truck-bolster by 100 means of rivets passing through the top plate and the outwardly-turned flanges.

As a filler king-pin block I provide the casting 16, Fig. 4, which has oppositely-extending flanges at each end riveted to the 105 side plates 1 1. The central portion of the block has a hub 18 with a cylindrical bearing through its center. The truck-bolster is sup-

plied with a similar block and the king-pin 19 when in place passes through and has its bearings in the two hubs 18, as is illustrated in Fig. 9.

5. It will be apparent to those skilled in the art that I have devised an extremely simple and at the same time unusually strong form of bolster which may be used either as a body bolster or a truck-bolster, or both.
10. Various modifications may be made in the structure herein described which would fall within the spirit and scope of the invention as defined in the following claims.

This patent is intended to embrace only so much of the disclosure made herein as is covered by the claims.

I claim—

1. In a bolster, the combination of spaced bellied side plates, and a bottom tie-plate 20 broadest at its central portion and tapering toward its ends fastened to said side plates, substantially as described.
2. In a bolster, the combination of bellied side plates, a top plate riveted to said side 25 plates, and a tapering bottom plate riveted to said side plates, substantially as described.
3. In a bolster, the combination of bellied side plates with top and bottom flanges, a rectangular plate riveted to the top flanges of 30 said side plates, and a tapering plate riveted to the bottom flanges of said side plates, substantially as described.
4. In a bolster, the combination of bellied side plates with top and bottom flanges, a rectangular plate riveted to the top flanges of 35 said side plates, and a tie-plate broadest at its center and tapering toward its ends riveted to the bottom flanges of said side plates, substantially as described.
40. 5. A bolster provided with a side plate hav-

ing an integral bottom flange turned laterally in one direction, and another integral bottom flange turned laterally in the opposite direction, substantially as described.

6. A bolster provided with a side plate having 45 a top flange extended in one direction, a bottom flange extended in the same direction, and another bottom flange extended in the opposite direction, substantially as described.

7. A bolster provided with a side plate having 50 an integral top flange turned in one direction, an integral bottom flange turned in the same direction, and another integral bottom flange turned in the opposite direction, substantially as described.

8. A bolster comprising two side plates 55 having outwardly-turned upper flanges, and inwardly and outwardly turned lower flanges, a plate riveted to the upper flanges, and a second plate riveted to the lower flanges, substantially as described.

9. In a bolster, the combination of two side plates having outwardly-turned upper flanges, and inwardly and outwardly turned lower flanges, of a plate riveted to the upper 65 flanges, and a tapering plate riveted to the lower flanges, substantially as described.

10. In a bolster, the combination of two side plates having outwardly-turned upper flanges and inwardly and outwardly turned 70 lower flanges, of a plate riveted to the upper flanges, and a second plate broadest at its center and tapering toward its ends riveted to the lower flanges, substantially as described.

ETHAN I. DODDS.
